[57] CLAIM

The ornamental design for a combined handset tele-
phone and interlocking cradle stand assembly, substan-
tially as shown.

DESCRIPTION

FIG. 1 is a perspective view of a combined handset telephone and interlocking cradle stand assembly showing my new design;

FIG. 2 is a side elevational view thereof;

FIG. 3 is a front elevational view thereof;

FIG. 4 is a rear elevational view thereof;

FIG. 5 is a top plan view of the handset of the assembly;

FIG. 6 is a side elevational view of the handset;

FIG. 7 is a bottom plan view of the handset;

FIG. 8 is a front elevational view of the handset;

FIG. 9 is a rear elevational view of the handset;

FIG. 10 is a top plan view of the cradle of the assembly
with the handset removed therefrom;

FIG. 11 is a side elevational view of the cradle;

FIG. 12 is a bottom plan view of the cradle;

FIG. 13 is a front elevational view of the cradle; and

FIG. 14 is a rear elevational view of the cradle.

Components of the assembly are shown separately for
clarity of illustration and exposure.
